Primary Examiner — Mary Ann Calabrese*Assistant Examiner* — Katelin G Kloberg(74) *Attorney, Agent, or Firm* — CANTOR COLBURN LLP(57) **CLAIM**

The ornamental design for a bed desk, as shown and described.

DESCRIPTION

FIG. 1 is a perspective view of a bed desk showing my new design in a closed position;

FIG. 2 is a front elevation view of the bed desk of FIG. 1; FIG. 3 is a rear elevation view of the bed desk of FIG. 1; FIG. 4 is a top plan view of the bed desk of FIG. 1; FIG. 5 is a bottom plan view of the bed desk of FIG. 1; FIG. 6 is a left side elevation view of the bed desk of FIG. 1;

FIG. 7 is a right side elevation view of the bed desk of FIG. 1; and,

FIG. 8 is a perspective view of the bed desk of FIG. 1 in an open position.

The broken lines in the drawings illustrate portions of the bed desk that form no part of the claimed design.

1 Claim, 7 Drawing Sheets(56)
